LOADING MACHINE GATHERING CHAIN

Frank Cartlidge, Chicago, Ill., assignor to Goodman Manufacturing Company, Chicago, Ill., a corporation of Illinois

Application November 10, 1933, Serial No. 697,415
Renewed December 21, 1936

11 Claims. (Cl. 262—33)

This invention relates to improvements in gathering or cutting chains for loading or mining machines and has among other objects to provide a new and improved chain of the class 5 described, arranged in a novel manner to efficiently gather coal and cut snubbing kerfs in unsevered or tight coal.

My invention may be more clearly understood with reference to the accompanying drawing 10 wherein:

Figure 1 is a side elevation of a loading head of a loading machine with parts broken away and in section showing one form in which my invention may be embodied;

15 Figure 2 is an enlarged view of the forward portion of the device shown in Figure 1 with certain parts broken away and in section, showing several details of my invention not shown in Figure 1; and

20 Figure 3 is an enlarged fragmentary detail plan view of the device, illustrating certain details of one of the gathering arms and the manner in which it is connected to the chain.

In the drawing one embodiment of my invention is shown as being applied to a gathering head for loading machines, of a type such as is shown in a prior application, Serial No. 472,701, filed by me August 2, 1930, although it will be apparent that it may be applied to cutter chains for 25 mining machines as well as to a gathering chain for loading machines. In the form shown, endless chains 10, 10 are provided which are orbitally movable about guides 11, 11 of an ordinary construction. Said guides are secured to 30 opposite sides of an inclined apron 12 of a gathering and loading element 14 and extend along and are spaced above opposite sides of an inclined conveyor 15 from a point disposed forwardly of the forward end thereof for gathering 35 and moving material thereon. The angle of inclination of the guides 11, 11 is herein shown as being parallel to the angle of inclination of the apron 12 to a point adjacent the forward end thereof, from which point the angle of inclination of said guides is substantially parallel 40 with the ground when said gathering and loading element is in engagement with the ground, to enable the gathering mechanism to move along and gather material from the ground.

45 The chain 10 is made up of a series of chain blocks 17, 17 pivotally connected together by a series of straps 18, 18. This chain rides in a groove formed in the guide 11 and is driven by a sprocket in the usual manner. Said groove is 50 provided at its top and bottom surfaces with

suitable guideways 19, 19 (see Figure 2) in which restraining lips 20 on the straps 18 are retained.

The gathering chain 10 is provided with suitable gathering means pivotally connected thereto at spaced intervals therealong which are herein shown as being laterally projecting gathering arms 21, 21 pivotally connected between parallel spaced lugs 18a, 18a projecting from certain straps 18, 18, for pivotal movement with respect thereto about axes perpendicular to the plane of movement of said gathering chain and spaced forwardly of the longest axis of each of said arms. The gathering arms 21, 21 are so spaced as to prevent interference between each other and each gathering arm has a gathering face inclined rearwardly from the lower forward side thereof as is best shown in Figure 3. Each of said arms also has a cutter bit 22 projecting laterally from its outer end and a projection 23 disposed intermediate its ends which extends angularly outwardly and upwardly therefrom. Said projection is adapted to carry a cutter bit 24 which is adapted to cut clearance for the arm and snub unsevered or tightly wedged coal. Pivotal movement of each gathering arm 21 with respect to the straps 18 is limited by supporting legs 25 and 26 extending forwardly and rearwardly therefrom from a point disposed adjacent the pivotal axis thereof, which are adapted to engage said chain. The gathering arms 21 besides gathering and moving material onto the inclined conveyor 15 may also cut and loosen solidly wedged material or may cut a snubbing kerf in the coal face if desired.

With reference now in particular to the details of construction of the chain 10 each chain block 17 is made from a pair of members 27, 27. Each member 27 has a slightly concave or bowl shaped socket 28 formed adjacent its opposite ends and extending therethrough so that the diameter of the opening on one side of said member is greater than the diameter of the opening on the opposite side of said member. The sockets 28, 28 may be formed in any suitable manner, such as boring or drop forging.

Bearing members 29, 29 are provided and are adapted to fit in the sockets 28, 28 formed in the members 27. Each bearing member 29 is formed with a continuous convex face having flattened ends and is bored along a line coaxial with the longest axis of said member to receive a connecting member or rivet 30 adapted to extend equidistantly beyond the ends thereof. The bearing members 29 are adapted to be inserted in the

55

concave sockets 28, 28 of one of the members 27. The other member 27 is then fitted over the bearing members 29 so the two members and the widest openings of said sockets abut each other, thus forming ball and socket connections between the straps 18, 18 and the chain block 17. The members 27, 27 may be secured together in any suitable manner, but are herein preferably shown as being welded together. The members 10 27, 27 being secured together to form the block 17, the straps 18, 18 may be secured to the outer ends of the rivets 30, 30 in a usual manner so that their inner surfaces abut the ends of the bearing members 28, 28.

15 While I have herein shown and described one form in which the device of my invention may be embodied, I wish it to be understood that I do not desire to be limited to the precise details or form of construction shown herein, excepting 20 as it may be limited in the appended claims.

I claim as my invention:

1. An endless chain gathering device including a series of interconnected links, a plurality of spaced apart laterally projecting gathering arms, 25 each of said arms being pivotally connected to certain of said links for limited pivotal movement about an axis perpendicular to the plane of travel of said chain, each of said gathering arms having a cutter bit projecting therefrom 30 and having forwardly and rearwardly extending legs adapted to engage said chain and limit pivotal movement of said arms beyond a certain predetermined point in either a forward or rearward direction.

35 2. An endless chain gathering device including a series of interconnected links, a plurality of spaced apart laterally projecting gathering arms, each of said arms being pivotally connected to certain links of said chain for limited pivotal movement about an axis disposed perpendicular to the plane of travel of said chain, each of said gathering arms having a leg projecting forwardly therefrom from a point disposed adjacent its axis of pivotal connection to said chain and 40 another leg projecting rearwardly therefrom from a point disposed adjacent its axis of pivotal connection to said chain, said legs being adapted to engage said chain and limit pivotal movement of said arms in either a forward or rearward direction beyond a certain predetermined point.

45 3. In an endless chain gathering device, a series of interconnected links, spaced apart laterally projecting gathering arms pivotally connected between pairs of parallel spaced lugs projecting from certain of said links, each of said arms being pivotally movable about an axis disposed perpendicular to the plane of travel of said chain and spaced forwardly of the longest central axis of said arm, and means for limiting pivotal movement of said arms about said axes comprising a leg extending forwardly from each of said arms from a point disposed adjacent its pivotal axis and adapted to engage said chain forwardly of said arm, and another leg extending rearwardly from each of said arms from a point disposed adjacent its pivotal axis and adapted to engage said chain rearwardly of said arm.

50 4. In an endless chain gathering device, a series of interconnected links, a plurality of spaced apart laterally projecting gathering arms, each of said arms being pivotally connected between pairs of parallel spaced lugs projecting from certain of said links for pivotal movement about an axis disposed perpendicular to the plane of travel

5 of said chain and spaced forwardly of the longest central axis of said arm, means for limiting pivotal movement of said arms about said axes comprising a leg extending forwardly from each of said arms from a point disposed adjacent its pivotal axis and adapted to engage said chain forwardly of said arm, and another leg extending rearwardly from said arm from a point disposed adjacent its pivotal axis and adapted to engage said chain rearwardly of said arm, each 10 of said gathering arms having a cutter bit projecting from the outer end thereof and another upwardly projecting bit disposed intermediate the ends thereof, and said rearwardly projecting legs holding said arms in position whereby said bits may cut clearance for said arms and cut a snubbing kerf in a mine wall.

15 5. In an endless chain gathering device, a series of interconnected links, spaced apart laterally projecting gathering arms pivotally connected to certain of said links for limited pivotal movement about axes perpendicular to the plane of travel of said chain, each of said arms having a forward gathering face inclined upwardly and rearwardly from the lower end thereof and having one cutter bit projecting laterally from the outer end thereof and another cutter bit projecting upwardly from a point disposed intermediate the ends of said arm, and means extending forwardly and rearwardly from each of said arms for limiting pivotal movement thereof and holding said arms in position whereby said bits may cut clearance for said arms and cut a snubbing kerf in a mine wall.

20 6. A gathering and cutting chain comprising a series of blocks connected together by a series of straps, gathering arms pivotally connected to certain of said straps at spaced intervals therealong for pivotal movement about an axis perpendicular to the plane of travel of said chain, 25 each of said gathering arms having cutting means carried thereby and a pair of legs extending forwardly and rearwardly therefrom for engagement with the next adjacent forward and rearward blocks for limiting pivotal movement of said arms 30 beyond certain predetermined points.

35 7. A gathering and cutting chain comprising a series of blocks connected together by a series of straps, gathering arms pivotally connected to certain of said straps at spaced intervals therealong for pivotal movement about an axis perpendicular to the plane of travel of said chain and spaced forwardly of the longest central axis of said arms, and means for limiting pivotal movement of said arms about said axis comprising a leg extending forwardly from said pivotal axis and adapted to engage the next adjacent forward chain block and another leg extending rearwardly of said pivotal axis for engagement with the adjoining rearward chain block.

40 8. A gathering and cutting chain comprising a series of blocks connected together by a series of straps, gathering arms pivotally connected to certain of said straps at spaced intervals therealong for pivotal movement about an axis perpendicular to the plane of travel of said chain and spaced forwardly of the longest central axis of said arms, means for limiting pivotal movement of said arms about said pivotal axis comprising a leg extending forwardly from said pivotal axis and adapted to engage the next adjacent chain block and another leg extending rearwardly of said pivotal axis for engagement with the adjoining rearward chain block, and means whereby said gathering arms may cut a snubbing 45

kerf in the mine wall comprising a cutter bit extending from the outer end of each of said gathering arms and another cutter bit extending upwardly from each of said gathering arms.

5 9. Gathering and cutting mechanism comprising a series of links pivotally connected together for movement in a closed orbital path, a gathering and cutting arm extending outwardly from one of said links and pivotally connected thereto 10 for pivotal movement about an axis perpendicular to the plane of travel of said chain, said arm having a forward portion forming a material gathering surface and having a cutter bit extending outwardly and forwardly from the forward end thereof and another cutter bit extending upwardly and forwardly from the upper side thereof, and means for limiting pivotal movement of said arm with respect to its associated link comprising a leg extending forwardly therefrom for engagement with the next adjacent forward link and another leg extending rearwardly therefrom for engagement with the next adjacent rearward link.

10 10. Gathering and cutting mechanism comprising a series of links pivotally connected together for movement in a closed orbital path, a gathering and cutting arm extending outwardly from one of said links and pivotally connected thereto for pivotal movement about an axis perpendicular to the plane of travel of said chain, means for limiting pivotal movement of said arm in a forward and rearward direction beyond a certain predetermined point comprising a leg

extending forwardly from said arm and adapted to engage said next adjacent forward link and another leg extending rearwardly from said arm and adapted to engage said next adjacent rearward link, and means whereby said arm may 5 cut a snubbing kerf in the mine wall comprising a cutter bit extending forwardly from the outer end thereof and another cutter bit extending upwardly and angularly forwardly and outwardly therefrom.

10 11. Gathering and cutting mechanism comprising a series of links pivotally connected together for movement in a closed orbital path, a gathering and cutting arm extending outwardly from one of said links and pivotally connected thereto for pivotal movement about an axis perpendicular to the plane of travel of said chain and spaced forwardly of the longest central axis of said gathering arm, said arm having a forward portion forming a material gathering surface 20 and having a cutter bit extending outwardly and forwardly from the forward end thereof and another cutter bit extending upwardly and forwardly from the upper side thereof, and means for limiting pivotal movement of said arm beyond certain predetermined points comprising a leg extending forwardly from said pivotal axis and adapted to engage the next adjacent link and another leg extending rearwardly of said pivotal axis for engagement with the adjoining rearward link.

15 25 30 FRANK CARTLIDGE.
